UNITED STATES PATENT OFFICE.

FRANK HINMAN PIERPONT, OF HORLEY, ENGLAND, ASSIGNOR TO LANSTON MONO-TYPE MACHINE COMPANY, OF PHILADELPHIA, PENNSYLVANIA, A CORPORATION OF VIRGINIA.

MATRIX-CASE EQUIPMENT FOR TYPE-CASTING MACHINES.

Application filed February 19, 1924. Serial No. 693,853.

To all whom it may concern:

Be it known that I, FRANK HINMAN PIERPONT, a citizen of the United States of America, residing at Salfords, Horley, in the county of Surrey, England, have invented certain new and useful Improvements in Matrix-Case Equipments for Type-casting Machines; and I do hereby declare the following to be a full, clear, and exact 10 description of the same, reference being had to the accompanying drawings, forming part of this specification, and to the characters of reference marked thereon.

This invention relates to matrix or die case equipment for type casting and similar typographic machines and refers to matrix cases in which the matrices are assembled in a frame in rows and columns. A matrix case of the kind referred to, as well as a 15 machine in which it is adapted to be employed, is basically disclosed in United States Letters Patent No. 625,998, dated May 30, 1899. In such a matrix case the matrices are oblong blocks, rectangular in 20 cross section, one end being furnished with a character or formative cavity and the other end with a centering cavity usually conical in shape for engagement with a centering device for clamping or pressing each 25 matrix against the mold when a cast is to be made.

The main object of the present invention is to provide means for limiting the side 30 and other wearing movements of individual matrices in the case, and at the same time allowing a matrix or matrices to be removed therefrom without removing the entire series; and also means which will support and guide the matrices during centering movements, the matrices being so constructed as to co-operate with said guiding means, while sufficient of the original outside walls of the 35 matrices is left to provide adequate bearing surface between matrices. Other objects 40 will be hereinafter pointed out or will otherwise appear in connection with the description of the invention as embodied in the accompanying drawings in which—

Fig. 1 is an inverted plan of a matrix case 45 embodying the present invention, the matrices being omitted.

Fig. 2 is a vertical section on approxi- 50 mately line 2—2 of Fig. 1,

Fig. 3 is a vertical section of a matrix case including the matrices on approximately line 3—3 of Fig. 4.

Fig. 4 is a horizontal section on approximately line 4—4 of Fig. 3, the matrix case frame being shown in inverted plan.

Fig. 5 is a side elevation of a matrix embodying the present invention, and

Fig. 6 is a plan of said matrix.

The matrix frame 1 is of a usual and well-known construction being box-like and having an opening through it for the accommodation of a series of matrices arranged in rows and columns. On the top of the frame 1 is a cover plate 2 provided with a series of perforations or openings 3 coinciding, when the matrices 5 are assembled in the matrix 55 case, with the centering cone holes 4 in the matrices. In the present embodiment of the invention, the matrices 5 are suspended on a series of parallel transverse bars or rods 6 which pass through lateral bores or openings 7 in the bodies of the matrices and are carried in bearings in two opposite walls of the frame 1, the construction being well-known and being described, for example, in the patent referred to. These suspension 60 rods of the patented construction are so arranged that each rod suspends or supports a row of matrices: while these rods limit to some extent the lateral movements of the matrices of a row in one direction, they allow in the other direction the accumulated 65 wear of a column of matrices to result in the displacement of any matrix of that column to a harmful extent. They also permit matrices to turn or tilt in an undesirable manner.

In accordance with the present invention, this is prevented by the provision of a series of projections extending downwardly from the cover plate 3 and fitting into spaces between the matrices formed by cutting 70 away the latter at their upper ends. The projections on the cover plate 3 are indicated by the reference character 8, and, as shown, are integral with the cover plate although they may be carried on a separate 75 plate. Each projection is of square section (Fig. 1) and extends downwardly within the opening in the frame of the matrix case.

The upper end 9 of each matrix 5 from a 80 line slightly above the suspension hole 7 is

2
of octagonal shape, this shape being formed by cutting away the four corners of the body. Thus when the matrices are assembled (Fig. 4) the four walls of the octagonal part 9 which have not been cut away will bear against the four neighboring matrices and the other four walls of said octagonal portion will bear against and be guided by the projections 8. The walls of 10 the lower or square portion of a matrix will be in close contact with the similar portions of neighboring matrices.

The projections 8 extend approximately to the shoulders of the matrices formed by cutting away the corners and fit the matrix spaces produced by this cutting: and the projections thus guide and maintain the matrices in an upright position especially during centering movements, as well as 20 limit the lateral movements of individual matrices. The matrices are thus supported in a function to prevent undue wear by tilting or rubbing and to prevent displacement by accumulated wear.

25 When it is necessary or desired to remove a matrix from the matrix case, a plate 10 (Figs. 1 and 4) the ends of which are supported in slots or recesses 11 at one end of the frame 1, is removed to uncover the ends 30 of the suspension rods 6: the rod supporting the row in which the required matrix is situated may obviously be removed after which the said matrix may be pushed out of the matrix case by passing a thin rod or 35 the like up through the centering opening 3 in the cover plate 2, this being accomplished without disturbing any other matrix: and a fresh matrix may then be dropped into the vacant space and the suspension rod 6 and end plate 10 replaced.

40 I claim:

1. A matrix case comprising a frame, a series of matrices arranged therein in rows

and columns, said matrices being cut away at their upper ends to form spaces, and a 45 plate provided with a series of projections fitting into said matrix spaces, said plate being supported on said frame.

2. A matrix case comprising a frame, a series of matrices arranged therein in rows 50 and columns, the corners of said matrices at their upper ends being cut away to form spaces between them, and a plate provided with a series of projections fitting into said matrix spaces, each projection forming a 55 guide or bearing for four matrices.

3. A matrix case comprising a frame, a series of matrices therein in rows and columns, each of said matrices being provided with transverse holes and at their upper ends 60 being cut away to form spaces between them, a series of parallel transverse suspension bars passing through the holes of a row of matrices, and a plate provided with a series of projections fitting into said matrix 65 spaces, each projection forming a matrix guide.

4. A matrix case comprising a frame, a series of matrices arranged therein in rows and columns, said matrices at their upper 70 ends being cut away to form spaces, and a cover plate for the frame, said plate being provided with perforations for matrix centering purposes, and being also provided with a series of projections fitting into said 75 spaces to form matrix guides.

5. A typographic matrix comprising a rectangular block having an upper end octagonal in cross section and having a rectangular lower or body portion. 80

6. A typographic matrix comprising a rectangular block having a square body portion provided with a transverse opening therethrough, the upper end portion of the block being octagonal in cross section.

FRANK HINMAN PIERPONT.
